UNITED STATES PATENT OFFICE.

EDWARD L. CONKEY, OF BOSTON, MASSACHUSETTS.

IMPROVEMENT IN OILERS FOR LOOSE PULLEYS.

Specification forming part of Letters Patent No. 124,333, dated March 5, 1872.

To all whom it may concern:

Be it known that I, EDWARD L. CONKEY, of Boston, in the county of Suffolk and State of Massachusetts, have invented a new and useful Improvement in Oilers for Loose Pulleys; and I do hereby declare the following to be a full, clear, and exact description thereof sufficient to enable those skilled in the art to which my invention appertains to make and use the same, reference being had to the accompanying drawing making part of this specification.

This oiler consists of a cup or vessel, suitable for containing the lubricating-oil employed, that is constructed with a passage leading to the journal or shaft on which the loose pulley turns, and is provided with a movable head or piston in such a manner that the revolution of the pulley, through its centrifugal action on the said head or piston, will force the oil through said passage to the journal. In addition to the above, the invention consists of a regulator in said oil-passage for regulating the supply of oil to the journal.

In the accompanying plate of drawing my improvements in oilers for loose pulleys are illustrated, the figure being a central vertical section of an oiler constructed according thereto, and as applied to the hub of a loose pulley-wheel.

A in the drawing represents the cup or receptacle of the oil for the oiler. This cup is provided with a cap or head, B, adapted to be screwed on and off for supplying the cup with oil, and is also provided with a plug, C, for being screwed into the hub of the pulley-wheel; *a*, a tubular passage, arranged in the present instance in the center of the cup, and extending from the bearing or journal of pulley nearly to the detachable cap or head B, forming a communication for the oil between the interior of cup A and the journal or bearing, as is obvious. D is a head or piston, arranged within the cup A so as to move therein from end to end thereof, its periphery being provided with leather or other suitable packing to form a close joint. This head moves over the central oil-tube *a*.

An oiler constructed as above described, with oil in the space between the piston or head D and the movable cap to the cup, will by

the revolution of the pulley throw the piston D by centrifugal force outward from the hub in direct proportion to the speed of the pulley, forcing, as is obvious, the oil in the cup through the passage *a* to the bearing or journal.

b, a screw located in cap B to cup A, and in position when screwed in sufficiently to enter the open end of oil-passage *a*, and thereby to open or close the same more or less to the flow of oil through it to the journal of pulley-wheel, according as may be found necessary to produce the proper lubrication of the parts; *c*, air-holes in each end of the bottom of oil-cup A for the admission of air to the chamber of oil-cup back of the movable head or piston to overcome the vacuum made by the movement of the piston through the revolution of the pulley, as described.

The oil-cup may be made with or without a removable cap, B; but it is most convenient for use when so constructed, as it enables both the piston to be inserted or removed at pleasure and the cup to be charged with oil. The oil-passage may be at one side in lieu of the center, and if desired more than one passage may be arranged, it being only necessary that they should communicate with oil-cup and bearing or journal for loose pulley, substantially as described.

Having thus described my invention, what I claim as new, and desire to secure by Letters Patent, is—

1. An oiler for loose pulleys, &c., having its oil-receptacle provided with a passage leading to the journal, a bearing of the pulley, and a head or piston, constructed and arranged together substantially as and for the purpose described.

2. In combination with the above, the regulator *b* or its equivalents to oil-passage, substantially as described, for the purpose specified.

3. The air-holes *c*, substantially as and for the purpose described.

The above specification of my invention signed by me this 1st day of May, A. D. 1871.

E. L. CONKEY.
